UNITED STATES PATENT OFFICE.

CHARLES E. JOHNSON, OF MUSKEGON, MICHIGAN.

AUTOMATIC PISTON-RING-GRINDING MACHINE.

Application filed January 9, 1922. Serial No. 528,076.

This invention relates to a machine for finish grinding piston ring castings at the ends thereof, this being one of the operations necessary to convert ring castings into finished piston rings. Prior to the finishing grinding of the castings at their ends, it is usual to rough grind the same to approximate form, with a removal of the scale and portions of the metal under the same, heavy and relatively coarse grinding wheels being used in such operation. This, however, cannot bring the casting at its ends to finished form with the thickness of the ring brought to proper limits of tolerance, and the final finishing grinding operation is necessary. The present invention is concerned with a machine in which the ring castings after the first rough grinding operation may be placed, and the same finish ground, the machine being designed for automatic working, that is, the machine is kept supplied with a quantity of the rough ground rings, from which they are taken one at a time and ground and thereafter dropped or ejected from the machine, finish ground at one end, being later finish ground at the other end in a like machine, or the same machine adjusted slightly differently. This invention has for its object and purpose, primarily, the provision of a machine by means of which the above defined ends may be attained efficiently and in a practical and satisfactory manner, large quantity production being had, with an elimination of skilled labor for the finish grinding operation, which has been necessary heretofore. Subsidiary to this primary purpose, are several other objects and purposes, having to do with the attainment of the ends noted in a simple manner and with the provision of mechanism which is positive, practically impossible to get out of order, durable and effective in every way. All of these, together with many novel constructions permitting and providing for the same, will appear fully and in detail as understanding of the invention is had from the following description, taken in connection with the accompanying drawings, in which,

Fig. 1 is a side elevation of a machine made in accordance with my invention.

Fig. 2 is a front elevation of the machine, with parts in vertical section to better disclose the construction.

Fig. 3 is a transverse vertical section through the machine substantially directly below the grinding wheel therefor and showing the vertical adjusting means therefor.

Fig. 4 is a plan view of the ring hopper and the individual ring selector therefrom for carrying the rings to the grinding wheel.

Fig. 5 is a horizontal section on the plane of line 5—5, of Fig. 3.

Fig. 6 is a view similar to Fig. 5, the ring hopper and ring selector being removed to show the construction under the same.

Fig. 7 is a horizontal section on the plane of line 7—7, of Fig. 2.

Fig. 8 is a vertical longitudinal section through the housing for the mechanism for operating the ring selector, said mechanism being shown in elevation.

Fig. 9 is a fragmentary vertical section substantially on the plane of line 9—9, of Fig. 8.

Fig. 10 is a fragmentary vertical section through a detail of the clutch mechanism shown in Fig. 8.

Fig. 11 is a view, similar to that shown in Fig. 8, the parts of the mechanism being in a different position, and

Fig. 12 is a sectional and side elevational view, taken on the plane of line 12—12, of Fig. 4.

Like reference characters refer to like parts in the different figures of the drawings.

The invention is adapted to be applied to and used in conjunction with a well known make of grinding machine, to me known as the Heald grinding machine, though the invention is not to be considered as restricted in use to the one type of machine. In such machines, the supporting or body casting 1 has a head 2 slidably mounted thereon for reciprocatory movements and at the front end of the head a grinding wheel 3, partially covered by a hood 4 is rotatably mounted. The machine is driven by a belt around pulleys 5. The mechanism for causing the reciprocation of the head 2 and the rotation of the grinding wheel is not outlined, as it is old and no part of the present invention.

At the front of the machine below the grinding wheel a relatively large vertically positioned sleeve 6 is located and connected with the body 1 and a second sleeve 7 is mounted for vertical adjustment in the

sleeve 6. At its upper end sleeve 7 carries a relatively stationary head 8 in which a magnetic chuck 10 is located, the same being secured at the upper end of a vertical shaft 9 mounted in bearings, one of which indicated at 11, at its lower end is carried in a member 12 located at the lower end of sleeve 7 and formed with a laterally extending arm 13 through which passes the lower threaded end of a vertical shaft 14 mounted on the outer sleeve 6. At its upper end shaft 14 carries a bevelled pinion 15 in mesh with a second pinion 16 which is fixed at the inner end of a short shaft mounted adjacent the upper end of sleeve 6, its outer end carrying a wheel 17 by means of which the shaft 14 may be turned through the gearing connections noted, and which may also serve as an indicating means for denoting the amount of vertical adjustment of the inner sleeve 7 and the parts carried thereby with respect to the outer sleeve 6. For this, the wheel 17 may be graduated and a pointer 18 fixed to extend thereover, as a means of indicating amounts of vertical adjustment. The inner sleeve 7 at one side is formed with a vertical slot or groove 19 into which the inner end of a stud 20 passing through the outer sleeve 6 extends to prevent rotative movement of the inner sleeve.

The lower end of the sleeve 7 is closed by a head 21 which, together with the member 12 is permanently connected to the sleeve by long screws 22 as shown. The head 21 has downwardly extending annular sides within the sleeve 6, being then turned outwardly and upwardly to make a continuous annular flange 23 around the lower end of the outer sleeve 6. Cast integrally with flange 23 are three arms 24, 25 and 26, of different lengths projecting from the flange at the front side as shown in Fig. 5. Rods 27, 28 and 29 are connected to the ends of said arms by means of nuts 30 and extend vertically from said arms. At the upper end of rod 27 an arc-shaped plate 31 is secured, its upper side being in the same plane with the upper side of the chuck 10 and having one end shaped so as to practically conform to the outer curved side of the chuck. Similarly, an arc-shaped plate 32 is carried at the upper end of rod 29 at the opposite side of the chuck, its end adjacent the chuck being shaped to conform to the curved outer side of said chuck. The plate 32 is longer than plate 31, for a purpose later appearing.

A housing 33 for certain parts of the mechanism of the invention is carried in front of the upper part of the sleeve 6 and is suitably connected permanently to the main body of the machine. This housing is provided with an arm 34 through which the rod 29 passes loose enough for sliding therein when a vertical adjustment of the inner sleeve and attached parts is to be made, the rod 27 likewise being guided in a member 35 having fixed connection to the stationary body of the machine.

The rod 28 passes upwardly through a sleeve 36 attached to the lower side of the housing 33 and into the housing, at its upper end being received in a downwardly extending hub 37 formed on a disk 38 which is fixed at the lower end of a vertical shaft 39 rotatably mounted in a bearing 40, which, together with a vertical sleeve 41 is cast integrally with the housing 33. The shaft 39 passes through the sleeve 41 and above the same, at its upper end having a head 42 which is formed with a depending skirt 43 to go over the upper end of the sleeve 41. Above the head a circular plate 44 is placed and detachably secured thereto by set screws. A thin sheet metal circular plate 45 is connected to the plate 44 and at equally spaced apart distances in the plate 45, circular openings are made of a size for receiving piston ring castings. The plate 45 is located so as to come directly over the plates 31 and 32 and the upper side of the magnetic chuck 10, as best shown in Fig. 4.

The disk 38 is constructed with a plurality of equally spaced radial slots 47. Paralleling the shaft 39 is a vertical shaft 48 mounted in a bearing 49 and to the shaft 48 two triangular plates 50 and 51 are secured, one over the other between which, at the corners are sleeves 52 mounted on rods 53 which connect the triangular plates at their corners (see Fig. 7). This construction is so located that on rotation of shaft 48, the sleeves 52 are brought to and enter the slots 47 in disk 38. In practice, there are six of the slots 47 and a like number of openings 46 in the circular plate which acts as a selector plate to carry the ring castings individually to the chuck 10. Shaft 48 at its upper end is equipped with a worm wheel 54 in mesh with which is a worm 55 fixed on the end of a shaft 56 which enters the housing 33 at one end, extending from said housing to the rear to a second housing 57 connected to the body 1 below the reciprocating head 2 mounted thereon.

The shaft 56 extends into housing 57 at one side, a second shaft 58, which is continuously driven in any suitable manner extending into the housing at the opposite side and being in alignment with shaft 56. A clutch member 59 is fixed on the end of shaft 58. On the adjacent end of the shaft 56, a sleeve 60 is splined, its end nearest the clutch member 59 being formed with coacting clutch teeth 61. The opposite end portion of the sleeve is grooved, as at 63, one side of the groove being shaped into a cam 62. A relatively thick disk 64 having a deep V-shaped notch 65 transversely thereof in one side is fixed on the shaft 56 a short distance from the sleeve 60, and a coiled spring 66 is placed

around the shaft between the disk and sleeve the tendency of which is to move the sleeve so that its clutch teeth 61 shall engage with the clutch member 59 to drive shaft 56 from 5 shaft 58.

A guide block 67 is secured to the inner side of the housing vertically above the disk and sleeve in which two rods 68 and 69 are slidably mounted for vertical movements, 10 both being normally pressed downwardly by springs 70. Each at its upper end is formed with a head 71 having conical upper sides below which is a groove 72 around each rod. Rod 68 at its lower end is pointed so as to 15 readily enter the notch 65, and the lower end of rod 69 is reduced in diameter and adapted to enter the groove 63 in the sleeve 60, as shown in Figs. 8 and 11.

Above the guide block 67 a trip block 20 is secured, having two oppositely inclined lower sides 74. A bar 75 is slidably mounted back of blocks 73 and 67 and at its upper end passes through the upper end of the housing 25 57. A member 76 is secured to and moves with bar 75, from opposite ends of which member latch bars 77 depend, being pivotally connected to member 76 at their upper ends and formed at their lower ends with inwardly extending projections 78 adapted to pass 30 into the grooves 72 and under heads 71 of the rods 68 and 69. The latch bars are normally impelled inwardly so as to enter the grooves when brought thereto by springs 79 attached to member 76 and bearing against 35 the latch bars. Each bar on its inner side is formed with a saw-tooth projection 80, adapted on the upward movement of the bar 75 with its attached member 76 and latch bars, to ride against the inclined under sides 40 74 of the trip block 73, thereby impelling the latch bars outwardly to disconnect the same from the heads 71. A coiled spring under tension is connected at its upper end to the member 76, and at its lower end to the guide 45 block 67, this spring 81 normally tending to draw the member 76 and bar 75 into lower position, as shown in Fig. 8, and thereby insure connection of the latch bars 77 with the heads 71.

The upper end of bar 75 has pivotal connection to one arm 83 of a bell crank lever pivotally mounted at 84 to the side of the body 1 of the machine, the other arm 85 of the lever extending upwardly into the path 50 of movement of a trip member 86 adjustably mounted in a horizontal guide 87 on the reciprocating head 2. On the rearward movement of the head, the arm 85 is struck by trip member 86 with the result that the bar 75 and attached mechanism is elevated, the latch bars 77, in engagement with the heads 71, as shown in Fig. 8, lifting both rods 68 and 69. The elevation of the former frees 55 the disk 64 and of the latter disconnects the lower end thereof from the sleeve 60 so that

the clutch parts 61 and 59 are immediately connected together and shaft 56 rotated. The continuation of the upward movement brings projections 80 against the inclines 74, thereby disengaging the latch bars from the 70 heads 71 and letting the rods 68 and 69 fall, the lower end of the rod 68 riding over the outer curved surface of disk 64 and the lower end of rod 69 entering the wider portion 75 of the grooves 63 in sleeve 60. The connection of the clutch parts causes a turning of the sleeve 60 until the cam portion 62 of the sleeve rides against the lower end of rod 69, whereupon the sleeve 60 is automatically moved to disconnect its clutch part 61 80 from the other clutch member 59. As soon as this is accomplished, or immediately after, the notch 65 in disk 64 comes to position to receive the lower pointed end of rod 68 which enters the notch and stops the mechanism from overrunning under momentum. Accordingly, it is evident that with each reciprocation of the head 2, there is one complete revolution of the shaft 56, it in turn operating through the mechanism associated 85 therewith to turn shaft 39 and the selector plate 45 attached thereto a part of a revolution, in the machine illustrated, one sixth of a revolution.

The support for the plate 32 at the upper 90 end of rod 29 has an outwardly extending arm 88 extending beyond the edge of the plate 45 and a vertical post 89 is secured to said arm 88. A member 90 is mounted on the post which passes through a slot 91 in 95 said member, the member resting on a collar 92 on the post and being secured in any position to which adjusted by a nut 92 threading on to the upper end of the post. A vertically positioned, trough-shaped ring 100 guide 93 is secured to the end of the member 90 and lies over the selector plate 45 (see Fig. 4). Ears 90^a project from the member 90, to which bars 94 are connected, a rod 95^a passing through the ears and ends of 105 the bars 94 and having nuts 95 on the ends to securely bind the parts together. A vertical retaining bar 96 is connected to the ends of bars 94 and supported thereby. The ring castings 97 which are to be ground are 110 placed in superimposed relation between the bar 96 and the guide 93.

The magnetic chuck is periodically energized, once with each reciprocation of the head 2. A second housing 98 alongside the 115 housing 57 houses switch mechanism for making and breaking an electric circuit for the energizing of the chuck, a switch lever 99 extending upwardly from within the housing and being moved back and forth when engaged by dogs 100 adjustably mounted in the guide 87 on reciprocating head 2. The specific construction of the 120 electric circuit and the switch mechanism for controlling the same is not shown, as this 125 130

feature is already old in the Heald machine.

With a construction of machine as described, the operation is as follows: The ring holder or hopper is kept filled wholly or partly with rings which have been rough ground on their ends, and said rings are positioned directly over the selector plate 45 in a position such that, when the plate is turned, its ring receiving openings 46 come under the rings and successively receive and take the lowermost ring in the stack of rings from the remaining rings. After the selector plate is moved a step or one sixth of a revolution, it stops with an opening 46 directly under the stack of rings. The movement of the selector plate is positive and its stopping at an exact predetermined point is positive. The rings received in the openings 46 are carried over under plate 32 to the magnetic chuck (see Fig. 4) and the plate, during its intervals of stopping has an opening 46 directly over the chuck, so that a ring therein is positioned centrally of the chuck when the selector plate stops. The chuck is energized and the ring magnetically attached thereto while the head 2 moves forward to carry the grinding wheel over the ring, it being evident that the ring is rapidly rotated about its central vertical axis by reason of its attachment to the chuck which is driven at high speed, and the grinding wheel is likewise rapidly rotated about its central horizontal axis. The upper end face of the ring is accordingly ground truly with the passage of the grinding wheel forward and back thereover. On the substantial completion of the rearward movement of the head 2, the arm 85 of the bell-crank lever is operated to make the selector plate turning mechanism effective, whereupon the plate is turned one sixth of a revolution to bring the next succeeding ring into position for grinding, the ring which has been ground passing from the chuck, which is inert during the movements of the selector plate, over the second under plate 31 and eventually dropping from the selector plate when it has passed by the end of said under plate 31. It may be received in any suitable receptacle.

The grinding of the rings proceeds continuously, one after the other and all that is needed in the way of labor is for the rings to be placed in the ring holder, this being done by unskilled labor. The operation is rapid and large quantities of rings may be finish ground on one end in short time. It is obvious that the other end may be finish ground in the same manner in a different machine of like construction, or in the same machine by merely adjusting the ring selector plate and the plates 31 and 32 a little higher, through operation of the setting wheel 17.

65 The machine is relatively simple, durable,

and particularly effective in operation. One very practical feature of the construction resides in the mechanical movement through which shaft 39 is turned by shaft 48. This is a modification of the Geneva stop movement and in the present construction has many valuable assets in the operation of the machine. In the first place it is absolutely positive, and when a stop is made, the parts are so positioned (see Fig. 7) that a positive lock is made to the turning of the selector plate 45 in either direction from the position at which it is stopped. A further feature is that at the beginning and at the end of the movement of the selector plate, said plate is moved much more slowly than at the intermediate portion of its movement, the starting of the plate into movement being relatively very slow and gradual and the absolute stopping thereof coming after it has been practically slowed down almost to a stop. This eliminates strains, any jerky movements and in all ways facilitates the operation of the machine.

In practice, the machine has proved its merit. Piston rings are made in large quantities and must be so made in practice in order to produce and sell them commercially, and the present machine is a very important step in eliminating costly skilled labor in finish grinding, and at the same time getting greater production per machine with a consequent lowering of overhead expense. Furthermore, every ring is perfectly ground and exactly the same, there being no variations due to the human element necessarily introduced in hand grinding of the rings by skilled labor. All of these features combine to make the invention one of merit.

I claim:

1. In combination, a support, a chuck carried thereby and mounted to turn about a vertical axis, a vertical rotatably mounted shaft, a thin circular plate attached at the upper end of the shaft having a plurality of equally spaced openings adapted to receive rings cut therethrough, said openings being brought in succession over the chuck on rotation of the shaft, a second vertical rotatably mounted shaft, a worm gear attached to the upper end thereof, a worm in engagement with said worm gear, a shaft to which said worm is secured, means for periodically rotating said last named shaft a single complete revolution, and means for driving the first vertical shaft from the second vertical shaft.

2. In combination, a support, a horizontally reciprocable head mounted at the upper end of the support, a rotatably mounted grinding wheel mounted at the front of the head, an auxiliary support mounted on the first support for vertical adjustment with respect thereto, means for vertically adjusting the auxiliary support with respect to

105

110

115

120

125

130

- the first support, a chuck rotatably mounted to turn about a vertical axis on said auxiliary support and positioned directly below the grinding wheel, a vertical shaft 5 rotatably mounted on the auxiliary support, a thin circular plate having ring receiving openings therein secured at the upper end of the shaft and passing over said chuck to bring said openings in succession 10 directly over the center of the chuck, means to turn the shaft and attached plate periodically a part of a revolution, and means to stop the plate with an opening therein over the chuck.
- 15 3. In combination, a main support, a grinding wheel mounted thereon, an auxiliary support adjustably mounted on the main support, means to adjust the auxiliary support to different positions, a rotatably 20 mounted magnetic chuck carried by the auxiliary support adjacent the grinding wheel and adjustable with the auxiliary support toward or away from the grinding wheel, and ring carrying means movably mounted 25 on the auxiliary support and adjustable therewith for carrying rings individually and in succession to the chuck for action thereon by the grinding wheel.
4. In combination, a support, a head carrying a grinding wheel reciprocably mounted 30 on the support at the upper end thereof, a chuck mounted to turn about a vertical axis below the grinding wheel, a vertically mounted shaft, a circular plate with ring 35 receiving openings therethrough attached to
- the upper end of the shaft and movable over the chuck, a drive shaft, mechanism interposed between the drive shaft and said vertical shaft for driving the latter by the former, means normally holding the drive shaft 40 and said mechanism separated, spring means for effecting connection of the same when said holding means is released, means actuated by movement of said head for releasing the holding means, and means for automatically disconnecting the drive shaft and said mechanism after the mechanism has moved the plate a predetermined distance.
5. In combination with a grinding machine having a chuck to hold rings to be 45 ground, a vertically mounted shaft, means for periodically turning the shaft a partial revolution, a circular plate fixed at the upper end of the shaft having a plurality of ring receiving openings therethrough moving over said chuck, a vertical post, a member at the upper end thereof located horizontally under the plate, an arm extending from said member, a post attached to said arm and extending vertically above the 50 plate, a vertically positioned trough-shaped member attached to the post and located over the plate, and a vertical bar attached to the post and spaced a distance from said trough-shaped member to hold a plurality 55 of rings in superimposed relation between said member and bar.

In testimony whereof I affix my signature.

CHARLES E. JOHNSON.
